UNITED STATES PATENT OFFICE.

ISAAC NEWTON ELLMAKER, OF STERLING, ILLINOIS, ASSIGNOR OF ONE-HALF TO JOHN CONLON, OF SAME PLACE.

SHEET-METAL PAIL.

SPECIFICATION forming part of Letters Patent No. 319,080, dated June 2, 1885.

Application filed February 26, 1885. (No model.)

To all whom it may concern:

Be it known that I, ISAAC NEWTON ELLMAKER, a citizen of the United States, residing at Sterling, in the county of Whiteside and State of Illinois, have invented certain new and useful Improvements in Sheet-Metal Pails; and I do hereby declare the following to be a full, clear, and exact description of the invention, such as will enable others skilled in the art to 5 which it appertains to make and use the same, reference being had to the accompanying drawings, and to letters or figures of reference marked thereon, which form a part of this specification.

15 My invention pertains to certain improvements in sheet-metal pails; and it consists, essentially, in a detachable base designed and adapted to be clamped upon the bottom of the pail after the same is otherwise completed.

20 In the drawings, Figure 1 is a side elevation of a pail embodying my invention. Fig. 2 is a view of the pail and the base detached from the pail, and Fig. 3 is a section of a part of Fig. 1.

25 A is a sheet-metal pail, which may be of any conformation, and constructed with either vertical or diverging sides.

B is a detachable metallic base, made, preferably, of hoop-iron galvanized. The upper 30 edge of the base B is drawn inward, so as to form an inwardly-extending flange, a. The juncture of the side of the pail with its bottom forms an annular bead or ridge, e, around the outside of the lower edge of the pail, and such flange a clasps the pail directly above such ridge, and the base B is held in place partly by friction and in part by the flange a engaging the annular recess formed on the exterior of the pail by the ridge e on one side

and the outward swell of the sides of the pail 40 on the other.

At equal distances on the inside of the base B and slightly below its upper margin are rigidly attached the stops or rests b, which, particularly in vessels having vertical sides, 45 serve to prevent the pail from settling too far into the base B.

The ends of the base B are adapted to pass each other, and are held together by a screw-bolt. 50

On the inner end of the base B is formed the horizontal slot d, through which from the outside of the base is passed the screw-bolt C, and by means of the slot d the base B is readily enlarged or reduced to fit different-sized 55 pails. *

The advantages of my invention are that by means thereof I am enabled to furnish bases of cheap material—to wit, hoop-iron, and attach the same to pails without either 60 riveting or soldering, and such base is much more durable than tin or sheet-iron bases, as well as much cheaper.

What I claim as my invention, and desire to secure by Letters Patent of the United 65 States, is—

The combination of the detachable base B, having flange a, and provided with the slot d and the bolt C, and the pail A, provided with the ridge e, substantially as shown, and for 70 the purpose described.

In testimony whereof I affix my signature in presence of two witnesses.

ISAAC NEWTON ELLMAKER.
